CLAIM

The ornamental design for a dresser with mirror, as shown and described.

DESCRIPTION

FIG. 1 is a perspective view of a dresser with mirror according to the invention;

FIG. 2 is a front elevational view thereof;

FIG. 3 is a side elevational view thereof; and,

FIG. 4 is a top plan view thereof.

The back of the dresser with mirror is flat and non ornamental.

Broken lines are environmental and not part of the claimed design.
